UNITED STATES PATENT OFFICE.

MILTON E. CHANDLER AND FRANK C. MOCK, OF CHICAGO, ILLINOIS.

AIR CLEANER.

Application filed September 9, 1921. Serial No. 499,468.

To all whom it may concern:

Be it known that we, MILTON E. CHANDLER and FRANK C. MOCK, citizens of the United States, residing at Chicago, in the county of Cook and State of Illinois, have invented a certain new and useful Improvement in Air Cleaners, of which the following is a full, clear, concise, and exact description, reference being had to the accompanying drawings, forming a part of this specification.

The invention relates to cleaning devices, and more specifically to dynamic devices for separating impurities from gaseous material.

One object of the invention is to improve the functioning of devices of this sort.

Another object is to simplify and cheapen the mechanical construction employed.

20 Further objects and advantages of the invention will become apparent as the description proceeds.

In the accompanying drawings:

Figure 1 is a central section, and Figure 2 25 a plan view of a device constructed according to our invention.

In the embodiment of the invention selected for illustration, the main shell 10 comprises a cylindrical portion 12, a conical portion 14 and a lower cylindrical portion 16 terminating in an outwardly directed lip 18. A diaphragm or baffle 20 closes most of the opening through the cylindrical portion 16, said diaphragm comprising a cylindrical portion 22 of somewhat smaller diameter than portion 16 and extending somewhat above the same, crowned by a conical cap 24. A lip 26 extends outwardly from the lower edge of the cylindrical portion 22 and is apertured as at 28.

A lower chamber is defined by another shell having a conical portion 30, a cylindrical portion 32 and a final cone 34 open at its lower end. The upper edge of cone 30 is beaded around lips 18 and 26 as at 36 to unite both shells and the baffle into a single rigid structure.

An ejector is supported on the cylindrical portion 32 of the lower shell, said ejector comprising a lateral passageway 38 and a downwardly directed venturi 40 having its throat substantially in the plane of the open lower end of cone 34.

At its upper end, the cylindrical portion 12 terminates in an outwardly extending lip 42, in which are formed a series of irregular

quadrilateral depressions, or cup-shaped pits 44. A sheet metal cover 46 has its outer periphery shaped with depressions 48 registering with depressions 44 in lip 42, and carries a centrally located tube 50 joined thereto by a reversely curved bead 52.

A series of combined spacers and inlet guides 54 are formed of flat pieces of sheet metal bent to form a V having unequal legs 65 both terminating at the outer periphery of the cover and lip 42. The guides 54 are held in place by wide short lugs 55 on their edges lying in pits 44 and 48 along two sides of each pit. The spaces between the guides 70 function as tangentially directed inlet passages, and certain of the spaces between the legs of the V house fastening bolts 56 for holding the parts together. The discharge is, in this instance, directed laterally by 75 means of a sheet metal elbow 58, having a lip 60 welded or otherwise suitably secured to bead 52. A screen 62 is preferably provided, encircling the annular series of inlet 80 passages between guides 54, to prevent particles of large size from entering the device.

The operation of the device is as follows:

Air entering the tangential inlet passages forms a vortex by means of which particles suspended in the mass, and of greater specific 85 gravity than the same are thrown against the outer wall 12 by centrifugal action, and, as the gas moves downward, against the conical wall 14 also. The stream is now deflected by wall 14 and crown 24 and rises 90 through the center of the device, making its exit through elbow 58. Non-gaseous particles of greater specific gravity than the gas passing through the device will be precipitated into the annular space between the cylindrical portion 16 and the inner cylindrical 95 wall 22, and fall through orifices 28 to be thrust out of the lower chamber by the ejector. When the device is employed in connection with an internal combustion engine, part or all of the exhaust gases are 100 passed through the dejector, and the elbow 58 is connected to the inlet passages of the engine.

Without further elaboration, the foregoing will so fully explain the gist of our invention, that others may, by applying current knowledge, readily adapt the same for use under various conditions of service, without eliminating certain features which 105 may properly be said to constitute the essential items of novelty involved, which items 110

are intended to be defined and secured to us by the following claims.

We claim:

1. In a dynamic cleaner, a cylindrical chamber, a cover for said chamber spaced therefrom to define an annular inlet and having an axial outlet tube integral therewith extending downwardly therefrom past the plane of said inlet, a series of guides for directing the entering flow tangentially, said guides spacing said cover from said chamber, and fastening bolts lying between the walls of certain of said guides to hold the cover in place. 40
2. In a dynamic cleaner, a chamber, a cover for said chamber spaced therefrom to define an annular inlet, guides for directing the entering flow tangentially, said guides spacing said cover from said chamber, and fastening bolts lying between the walls of certain of said guides out of the air stream to hold the cover in place. 45
3. In a dynamic cleaner, a cylindrical chamber and a cover having spaced opposed annular lips, registering irregularities of contour in said lips, and guides laid in contact with and held in alignment by said irregularities for directing the incoming flow tangentially. 50
4. In a dynamic cleaner, a cylindrical chamber and a cover having spaced opposed annular lips, registering irregularities of contour in said lips, and guides engaging said irregularities and positioned to direct the incoming flow tangentially. 55
5. In a dynamic cleaner, a cylindrical chamber and a cover having annular lips, registering irregularities of contour in said lips, and spacers engaging said irregularities to hold both cover and spacers in position. 60
6. In a dynamic cleaner, a cylindrical chamber, a cover, a series of duplicate guides having an open V shape spacing said cover from said chamber to define an annular inlet and arranged to direct the incoming flow tangentially, and tension members housed in said guides for holding said cover in place. 65
7. In a dynamic cleaner, a cylindrical chamber, a cover, and guides having an open V shape spacing said cover from said chamber to define an annular inlet and arranged to direct the incoming flow tangentially. 70
8. In a dynamic cleaner, a cylindrical chamber, a cover, and guides having an open V shape spacing said cover from said chamber to define an annular inlet. 75
9. A cover for a dynamic cleaner, comprising a flat circular portion embossed around its periphery to register with suitable inlet vanes, and having a central axial tube drawn integrally therefrom. 80
10. A cover for a dynamic cleaner, comprising a flat circular portion embossed around its periphery to register with suitable inlet vanes, and having a central axial tube drawn integrally therefrom in one direction from the plane of the cover, and another tube fastened in place on said circular portion to prolong said first mentioned tube in the opposite direction. 85

In witness whereof, we hereunto subscribe our names this 7 day of September 1921.

MILTON E. CHANDLER.
FRANK C. MOCK.
